CLAIM

The ornamental design for a display screen or portion thereof with icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with icon; and,

FIG. 2 is a front view of a display screen or portion thereof with icon.

The broken lines in the Figures, including the display screen, or portion thereof are for illustrative purposes only and form no part of the claimed design.
